UNITED STATES PATENT OFFICE.

CHARLES B. STOUGH, OF MONTICELLO, ILLINOIS.

IMPROVEMENT IN MACHINES FOR BORING AND WALLING WELLS.

Specification forming part of Letters Patent No. 172,202, dated January 11, 1876; application filed April 3, 1875.

To all whom it may concern:

Be it known that I, CHARLES B. STOUGH, of Monticello, in the county of Piatt and State of Illinois, have invented a new and Improved Well Boring and Walling Machine, of which the following is a specification:

The invention consists of a boring and earth-elevating apparatus, constructed and arranged as hereinafter described.

Figure 1 is a sectional elevation of the boring apparatus, contrived with an elevator for elevating the earth from the auger while the boring is going on. Fig. 2 is a detail of the elevator, partly in side elevation and partly in section. Fig. 3 is a horizontal section of Fig. 1. Fig. 4 is a plan of the bottom of an auger to be used with the elevator. Fig. 5 is a side elevation of Fig. 4. Fig. 6 is a sectional elevation of the auger to be used without the elevator, the section being taken on the line *x x* of Fig. 7. Fig. 7 is a plan of the bottom of Fig. 6. Fig. 8 is a sectional elevation, showing an enlarged view of the auger.

Similar letters of reference indicate corresponding parts.

A is the frame for supporting and carrying the apparatus. It is mounted on wheels *B* for making it portable. On the top it has a circular way, *C*, by the side of which is a stationary toothed rim, *D*. The rim gives rotary motion to a shaft, *E*, which is mounted on a horizontal frame, *F*, to which the power is applied by a sweep or otherwise, and which revolves on the way *C*. This frame *F* is kept in position by the guide-wheels *G* on vertical studs *H*, running against the inner circular edge *I* of the frame *A*. A square section, *J*, of the auger-shaft is arranged between the rollers *K* of a beam, *L*, carried on the frame *F*, and is revolved by them to turn the auger, and at the same time allow the shaft to settle down between them without obstruction as the auger works into the ground. This shaft extends upward above the beam and rollers, suitably for carrying the elevator-chain *M*, and supports a roller, *L*, therefor in a yoke, *O*, which is keyed onto the shaft, so as to be extended for tightening the chains. In the yoke *P*, by which the auger *Q* is attached to the shaft, is another roller for the elevator at the

bottom, and on the shaft *E* are tappets *R*, or long teeth, which mesh with the links of the elevator-chain to work it. Guards *S* are contrived in front of these tappets to keep the links from slipping off from them. *T* is the spout into which the elevator-buckets *U* dump. It is mounted on the frame *F* to turn with the elevator and the auger, and has a tilting portion, *V*, of the bottom to extend under the buckets, to catch the earth and swing up to let the buckets pass.

The auger-shaft is lengthened out from time to time as the well deepens by round sections *q*, coupled in below the revolving frame *F*, a number being carried on the racks *r* in reserve, to be used as wanted.

The small auger is composed of three arms, *A'*, attached to the shaft *F''* near the point, and bent upward from the point to make a conical shape, on which arms are fastened bottom plates *H'* and a band, *I'*, and one of them carries the bit *q'* in a throat made in the bottom plates for the passage of the earth up into the case *J'*. This case rests on the band *I'*, and is connected, by loops *m'*, with the vertical parts of arms *K'*, which connect the band *I'* with the auger-shaft *F'* near the upper end, so that the case can slide up along them readily to open for dumping.

The auger-shaft connects with the coupling *P'* by entering a socket in the lower end, where it is secured by a self-locking catch, *L'*, which is used to connect and disconnect the auger-bottom with the case *J'* for dumping, the case being connected to coupling *P'* by arms *n'*. The coupling also carries reamers *q'* on arms *R'*, for reaming out the well larger than the auger. The arms *R'* are keyed in the coupling, so as to lengthen and shorten for varying the size. *E''* is the sand-valve of the auger.

Having thus described my invention, I claim as new and desire to secure by Letters Patent—

1. The combination of the frame *A*, circular way *C*, stationary toothed rim *D*, horizontally-revolving frame *F*, beam *L*, and the rollers *K* with the auger-shaft *J*, substantially as specified.

2. The combination of the shaft *E*, pinion *E'*, and tappets *R* with the stationary toothed

rim D, horizontally-revolving frame F, and the elevator, substantially as specified.

3. The arms A', shaft F', plates H', and rim I', combined and arranged to form the auger-bottom, substantially as specified.

4. The combination of case J', rim I', and arms K', substantially as specified.

5. The case J', arms n', coupling P', arms K', rim I', bottom H', arms A', and shaft F', combined substantially as specified.

CHARLES B. STOUGH.
